VENDING MACHINE

Ardon A. Bradt, Niagara Falls, N. Y.

Application April 3, 1940, Serial No. 327,650

6 Claims. (Cl. 312—47)

This invention relates to coin or token-operated vending machines and has for an object the provision of improved machines of the character referred to.

In the drawings, which are appended to aid in the understanding of the invention,

Figure 1 is a front view of the exterior of a machine embodying the present invention;

Figure 2 is a side elevation, partly broken away, of a mechanism embodying the present invention;

Figure 3 is a side view, partly in elevation and partly in section, of a mechanism embodying the present invention;

Figure 4 is a side view, in elevation, of a mechanism embodying the present invention;

Figure 5 is a rear view, in elevation, of a mechanism embodying the present invention;

Figure 6 is a front view, in elevation, of a mechanism embodying the present invention; and

Figure 7 is a plan view, taken as indicated by the line VII—VII of Figure 3, of a mechanism embodying the present invention.

The machine illustrated in the drawings is of the type that dispenses tokens, coupons or fortune telling cards, but it is to be understood that the invention is not limited to machines dispensing such articles because the drawings are for illustrative purposes and the machines can be adapted to dispense merchandise of substantially any description without departing from the scope of the invention. In the present disclosure, the term "token" will be used for simplicity of language, with the understanding that that term shall mean not only tokens of the usual sort, but also coupons of all sorts, fortune telling cards, and merchandise of the nature that can be dispensed by a machine.

Figure 1 shows the exterior of a machine comprising a case 1 having a coin slot 2 at the top, a window 3 through which the symbols 4, 5 and 6 are visible, a dispensing chute 7 and an operating handle 8.

Inasmuch as the coin receiving and handling mechanism does not form a particular part of the present invention, it will suffice to describe the machine of the present invention by starting with the coin-operated release lever 10 shown in Figure 2. When a coin of the proper denomination has been inserted in the slot 2, the release lever 10 is rotated counter-clockwise about the shaft 11 on which it is mounted and, as illustrated, permits the cam 12 to rotate counter-clockwise about the shaft 13 by the handle 8.

which is shown in Figure 1, but is not shown in Figure 2.

Located behind the cam 12, as viewed in Figure 2, is a lever 14 having a pin 15 projecting outwardly therefrom and rigidly attached thereto. Another pin 16 projects inwardly from, and is rigidly attached to, the cam 12. Between the cam 12 and the lever 14 is located a notched lever 17, and this notched lever is so positioned that the pin 15 on the lever 14 and the pin 16 on the cam 12 are embraced by the legs 18 and 19 of the lever 17. Thus, when the cam 12 is rotated counter-clockwise, the pin 16 urges the notched lever 17 in a clockwise direction and the movement thus produced causes the lever 14 to rotate in a counter-clockwise direction by virtue of the engagement of the leg 19 of the lever 17 with the pin 15, which is attached to the lever 14.

A link 20 connects the lever 14 with the reset lever 21, which is pivoted at 22. Thus, movement of the operating handle 8 causes the reset lever 21 to turn clockwise about its pivot 22 and engage the arm 23, which projects from the reset bar 24. Continued movement of the reset lever 21 causes the reset bar 24 to move forward and push the slide 26a forward so that the token opening 27 in the slide is directly under the stack 28a in which tokens are stored. When in this forward position, the opening 27 in the slide 26a permits a token to drop from the stack and rest on the plate 29, which supports the movable slide 26a.

The lever 14, which is referred to above in connection with Figure 2, is mounted on and pinned to the shaft 13, as shown in Figure 3. This shaft 35 13 is supported at one end by the frame member 32 and at the other end by the frame member 33, and projects beyond each of these frame members. At the end supported by the frame member 33, the main operating cam 12 is mounted on the shaft 13 and is free to turn thereon.

Thus, when the main operating cam 12, referred to in Figure 2, is operated in a counter-clockwise direction, the shaft 13, upon which the cam 12 is mounted, is caused to rotate in the same direction by virtue of the operation of levers 17 and 14, even though the cam 12 is not fixed on the shaft 13.

Also mounted on the shaft 13 are the levers 34, 35 and 36, which are fixed to the said shaft, and levers 37, 38, 39, 40, 41, 42 and 43, which are rotatable with respect to the said shaft, all of which are shown in Figure 5. The levers 37, 38 and 39 are joined by the member 44 to function as a unit.

The lever 34, which is fixed on the shaft 13,

operates the coin release mechanism briefly referred to hereinabove and is not of particular concern in this invention. The lever 35, which also is fixed on the shaft 13, serves to spin the reels 46, 47 and 48 by means of other levers not shown in Figure 3, but which are shown in Figure 5 and referred to again below.

Each of the reels 46, 47 and 48 is independently rotatable on the shaft 49, and each reel has attached to it two notched disks. As shown in Figure 3, the notched disks 51 and 52 are attached to the reel 46; the notched disks 53 and 54 are attached to the reel 47; and the notched disks 55 and 56 are attached to the reel 48.

The lever 37, to which levers 38 and 39 are joined, is connected to the rotatable shaft 61 by means of the slotted lever 62 and the pin 63. Also mounted on the shaft 61 and fixed thereto are the notched disks 64, 65, 66, 67, 68 and 69, which control the operation of the token-dispensing slides 26a, 26b, 26c, 26d, 26e and 26f (Figure 7) associated with the token magazines 28a, 28b, 28c, 28d, 28e and 28f.

The lever 36 contacts with the pin 71, which is fastened to the lever 43, and, as the shaft 13 is rotated by the handle 8, causes the lever 43 to rotate about the shaft 13. Rotation of the lever 43 causes the arm 72, which is fastened thereto, to move forward and also causes the spring 73, which has one end attached to the lever 43 and the other end attached to the pin 74, to be stretched. Rotation of the lever 43 also causes the gear train 75 to be set in motion by means of the link 76 that connects the lever 43 with the cam crank 77 fixed to the shaft 78 of the gear train 75. Thus, the gear train 75 is tensioned by the stretched spring 73 by virtue of the link 76 that connects the lever 43 with the cam crank 77, which is fixed to the shaft 78 of the said gear train, and, as the operation of the machine continues, the gear train is set into motion in the opposite direction by the said spring 73. The velocity of the operation of the gear train 75 is controlled by the vane 79 on the shaft 80.

Rotatably mounted on the shaft 81, which extends from the frame 32 on the one side to the frame 33 on the other side, is a wide U-shaped lever 82, which is connected to the lever-lifting arm 72 by a coil spring 83. Movement of the lever 43 causes the arms 72 to pull the U-shaped lever 82 by means of the spring 83, which connects these two members. The pull exerted upon the U-shaped lever 82 by the spring 83 causes the U-shaped lever 82 to rotate about the shaft 81, upon which it is mounted, and come under the ends of the levers 37, 38, 39, 40, 41 and 42 just after they have been raised by the arm 72. When the U-shaped lever 82 has moved under the levers 37, 38, 39, 40, 41 and 42, it remains there and holds those levers out of engagement with the notched disks 51, 52, 53, 54, 55 and 56 until the reversed direction of operation of the gear train 75 causes the lever 43 to move back toward its original position and bring into engagement with the U-shaped lever 82 by means of the pin 84 which is fixed on the lever 43. The backward movement of the lever 43, through the engagement of the pin 84 thereon and the lever 82, causes the lever 82 to be pushed back to its original position, whereby it moves out from under the levers 37, 38, 39, 40, 41 and 42 and permits them to re-engage with the notched wheels 51, 52, 53, 54, 55 and 56.

The restoration of the U-shaped lever 82 to its

original position also removes the detent lever 87 from under the cam 12 by virtue of the engagement of the leg 88 of the U-shaped lever 82 with arm 89 of the detent lever 87. The original movement of the U-shaped lever 82 removes the leg 88 thereof from engagement with the arm 89 of the detent lever 87 and permits the spring 90 to pull the detent lever under the cam lever 12 when it has been rotated by the operating handle 8 of the machine. When under the cam 12, the detent lever 87 prevents the cam 12 from returning to its original position until the cycle of operation of the machine has been completed. As the cycle of operation approaches completion, the leg 88 of the U-shaped lever 82 comes into engagement with the arm 89 of the detent lever 87 and pushes the arm 89 so that the detent lever 87 is moved back in opposition to the spring 90, which pulled it forward.

Figures 4, 5 and 6 show, among other things, the mechanism by which the dispensing slides 26a, 26b, 26c, 26d, 26e and 26f are reset at the beginning of the operation of the machine. As illustrated in Figures 2 and 3, the dispensing slide 26a is the dispensing position. The reset lever 21, immediately upon the operation of the machine being started, moves from the position shown in Figure 3 until it engages and pushes forward the reset bar pusher 24, which in turn urges the reset bar 93 against the leg 94 of whichever of the slides 26a, 26b, 26c, 26d, 26e or 26f (in this case 26a) that was left in the dispensing position by the previous operation of the machine, and pushes that slide into the non-dispensing position under its respective stack, 28a, 28b, 28c, 28d, 28e or 28f (in this case 28a). At the same time the reset bar 93 is being pushed forward, the link 76 connecting the lever 43 with the cam crank 77 rotates the cam crank 77 and permits the cam follower 95 to be urged to the lowest portion of the cam crank 77 by the spring 96. Such movement of the cam follower 95 causes the lever 97 to be moved into a position behind the reset bar 93 by virtue of the toggle joint 98. When the lever 97 is in the position behind the reset bar 93 just referred to, it prevents the reset bar 93 from being pulled away from the reset legs 94.

As described hereinabove, the rotation of the cam crank 77 just described also causes the gear train 75 to be set in motion against the action of the spring 73 (Figure 4). The link 76, and therefore also the cam crank 77, are driven by the lever 43 (Figure 4), which in turn is driven by the lever 36 fastened to the end of the shaft 13 (Figure 5).

The lever 36 drives the lever 43 until the pin 16 on the cam 12 (Figure 2) has urged the lever 17 to the point where the pin 16 no longer can urge the lever 17, whereupon the pin 16 passes by the leg 18 of the lever 17 and into a position on the opposite side of the leg 18.

The lever 17, being no longer urged by the cam 12, no longer urges the lever 14 by the engagement therewith of the pin 15, and consequently the shaft 13, to which the lever 14 is pinned, no longer is rotated in a counter-clockwise direction (Figure 2), but, on the other hand, is quickly returned to its original position by the contraction of the spring 99, one end of which is fastened to the lever 35, which is pinned to the shaft 13, and the other end of which is attached to the bottom frame of the machine.

The shaft 13 being returned to its original posi-

tion, the lever 36 also is out of engagement with and away from the lever 43. Consequently, the spring 73, which was stretched by the rotation of the lever 43, pulls the lever in the opposite direction and back to its original position. The return of the lever 43 to its original position is not free, however, but is controlled by the vane 79 of the gear train 75.

At the same moment the disengagement of the pin 16 on the cam 12 with the leg 18 of the lever 17 takes place, the lever 35 (Figure 3) has been rotated by the shaft 13 to such a position that the pin 101 has traveled to the opposite end of the slot 102 of the lever 103 and has caused the lever 103 to rotate counter-clockwise about the pin 104. The counter-clockwise movement of the lever 103 causes the lever 105 to rotate in a clockwise direction about the shaft 106 and hence also causes the lever 107, which is connected to the lever 105 in a slightly offset position, to rotate about the shaft 106 until the notch 108 in the lever 107 engages with a tooth in the notched wheel 52.

At the moment the notch 108 in the lever 107 has engaged a tooth of the notched wheel 52, the lever 40 has already been rotated by the shaft 13 so that the lever 40 is out of engagement with the notched wheel 52, and the lever 37 is out of engagement with the notched wheel 51. Thus, the reel 46 and the notched wheels 51 and 52, which are connected to the reel 46, are free to rotate on the shaft 49. The disengagement of the levers 37 and 40 with the notched wheels 51 and 52, respectively, is effected by the movement of the arm 72, which is fixed to the lever 43 (Figure 3), from the position shown in Figure 5 into urging engagement with the upwardly projecting legs of the levers 37 and 40. As referred to above, the movement of the arm 72 causes the U-shaped lever 82 to be pulled by the spring 83 into a position under the rearwardly projecting legs of the levers 37 and 40, which have been raised by the urging of the upwardly projecting legs by the arm 72 as described above. Having taken the position under the rearwardly projecting legs of the levers 37 and 40, the U-shaped lever 82 serves to hold the levers 37 and 40 out of engagement with the notched wheels 51 and 52, respectively, because the reverse movement of the arm 72 takes place sooner than that of the U-shaped lever 82. It should be noted here that although only the relationship of the lever 37 with the notched disk 51 and the relationship of the lever 40 with the notched disk 52 have been described in connection with Figure 5, the same relationship exists between the lever 38 and the notched disk 53, the lever 39 and the notched disk 55, the lever 41 and the notched disk 54, and the lever 42 and the notched disk 56, all of which are shown in Figure 3.

Similarly, it should be noted here that although only the relationship of the notched lever 107 with the notched disk 52 has been described in connection with Figure 5, levers similar to notched lever 107 and joined thereto to act as a unit have the same relationship to the notched disks 54 and 56 (Figure 3) and perform the same function as lever 107.

When, as described above, the notched lever 107 is in engagement with a tooth of the notched disk 52, and the levers 37, 38, 39, 40, 41 and 42 are held out of engagement with their respectively co-acting disks 51, 52, 53, 54, 55 and 56 by the U-shaped lever 82, the shaft 13, to which the lever 35 is attached, is snapped back to its original position by the spring 99.

The snapping back of the shaft 13 and the attached lever 35 causes the pin 101 to quickly rotate the lever 103 in a clockwise direction and thus quickly rotate the notched lever 107, which engages a tooth of the notched disk 52, in a counter-clockwise direction. The rapid counter-clockwise movement of the notched lever 107 causes the notched disk 52 and the reel 46 and notched disk 51, all of which are connected to act as a unit, to rotate rapidly and freely.

At the instant the notched disk 52 and the corresponding notched disks 54 and 56 are spun, the return movement of the gear train 75 is begun. The return movement of the gear train 75 causes the U-shaped lever 82, through the operation of the lever 43, to release first the levers 40, 41 and 42 in rapid succession, but not simultaneously, and the release of those levers brings to rest in the same sequence the reels 46, 47 and 48 by virtue of the engagement of the levers 40, 41 and 42 with the notched disks 52, 54 and 56, respectively.

When the reels 46, 47 and 48 have been brought to rest by the levers 40, 41 and 42, respectively, the levers 37, 38 and 39, acting as a unit, are released by the U-shaped lever 82 and re-engage with the notched disks 51, 53 and 55 (Figure 3).

Referring to Figures 3 and 4, it will be noted that the notched disk 55 contains radial notches of different depths and that the notches are of sufficient width to freely receive the arm 109 of the lever 39. The disks 51 and 53 are notched the same as notched disk 55 and on each of the levers 37 and 38, which are united to the lever 39, there is an arm similar to the arm 109 of the lever 39 that engages the notched disks 51 and 53, respectively.

As described above, the lever 37 is connected to the rotatable shaft 61 by means of a pin 63 and the slotted lever 62, which is fixed to the shaft 61. Also mounted on and fixed to the shaft 61 are the slotted disks 64, 65, 66, 67, 68 and 69. These slotted disks are so positioned on the shaft 61 that never more than one slot at a time is horizontal, and thus only one of the dispensing slides 26a, 26b, 26c, 26d, 26e and 26f can operate at a time by entering the slot in its respectively cooperating disk on the shaft 61.

The particular token-dispensing slide to operate at a given operation of the machine is determined by the positions the reels 46, 47 and 48, and consequently also the positions the notched disks 51, 53 and 55, take when they come to rest after they have been spun freely.

If the reels 46, 47 and 48 come to rest in such positions that the notched disks 51, 53 and 55 line up to permit the arm 109 of the lever 39 or the corresponding arm of either of the levers 37 or 38 to enter the shallowest slot, the lever 37 will move a corresponding distance and, by virtue of its being connected to the shaft 61, will rotate the shaft 61 the least amount, and will position one of the slotted disks 64, 65, 66, 67, 68 or 69 so that its slot will be horizontal and facing the dispensing slide 26a, 26b, 26c, 26d, 26e or 26f that is opposite that particular disk. In the particular arrangement of parts illustrated in the appended drawings, the dispensing slide 26a is operated when the lever 37 is permitted to travel the smallest distance.

In the event that the slotted disks 51, 53 and 55 so line up, when the reels 46, 47 and 48 come to rest, that they will permit the levers 37, 38 and 39, respectively, to enter the deepest slots, the lever 37 will move the greatest distance and

consequently rotate the shaft 61 the greatest amount. The particular arrangement of parts illustrated in the appended drawings permits the dispensing slide 26f to enter the slot in the disk 69 when the shaft 61 is rotated the greatest amount.

It will be obvious from the foregoing description that the distance the lever 37 can move is controlled by that one of the slotted disks 51, 53 or 55 that presents the shallowest notch of the three for entrance of the lever 37, 38 or 39 because the levers 37, 38 and 39 are united by the bar 44 and thus act as a unit, and if one notch shallower than the other two is presented, the united levers can enter their respective slots only to the depth permitted by that shallower slot.

While the foregoing description has been directed only to the operation of the dispensing slides 26a and 26f, it will be understood that the other slides 26b, 26c, 26d and 26e are operated in the same manner. The arrangement of parts illustrated in the appended drawings provides for the operation of the dispensing slides in alphabetical order as the amount of movement of the lever increases. Thus, the smallest movement of the lever causes the dispensing slide 26a to operate; the next greater amount of movement of the lever 37 causes the dispensing slide 26b to operate; and so on until finally the greatest amount of movement of the lever 37 causes the dispensing slide 26f to operate. At no time do two or more dispensing slides operate at the same operation of the machine, and hence only one token is dispensed at each operation of the machine.

Having thus described my invention, I claim:

1. In a vending machine, the combination comprising a plurality of token magazines having individual bottom closure means, spring means engaging said closure means and urging them to their open positions and a rotatable detent engaging said closure means and holding them in their closed positions against the action of said spring means.

2. In a vending machine, the combination comprising a plurality of token magazines having individual bottom closure means, spring means engaging said closure means and urging them to their open positions, a rotatable detent engaging said closure means and holding them in their closed positions against the action of said spring means, and selector means engaging said detent comprising an independently rotatable notched member and a lever having one end engageable with said notches and the other end engaging said rotatable detent.

3. In a vending machine, the combination comprising a plurality of token magazines having individual bottom closure means, spring means engaging said closure means and urging them to their open positions and a rotatable detent engaging said closure means and holding them in their closed positions against the action of said spring means, said rotatable detent comprising a shaft carrying a notched disk opposite each of said bottom closures, the said notched disks being positioned on said shaft with their respective notches angularly displaced from one another.

4. In a vending machine, the combination comprising a plurality of token magazines having individual bottom closure means, spring means engaging said closure means and urging them to their open positions and a rotatable detent engaging said closure means and holding them in their closed positions against the action of said spring means, said rotatable detent comprising a shaft carrying a notched disk opposite each of said bottom closures, the said notched disks being positioned on said shaft with their respective notches angularly displaced from one another.

5. In a vending machine, the combination comprising a plurality of token magazines having individual bottom closure means, spring means engaging said closure means and urging them to their open positions and a rotatable detent engaging said closure means and holding them in their closed positions against the action of said spring means, said rotatable detent comprising a shaft carrying a notched disk opposite each of said bottom closures, the said notched disks being positioned on said shaft with their respective notches angularly displaced from one another, and means for rotating said detent comprising a freely rotatable notched disk and a lever having one end in engagement with said detent and the other end engageable with the notches of said notched disk.

6. In a vending machine, the combination comprising a plurality of token magazines having individual bottom closure means, spring means engaging said closure means and urging them to their open positions and a rotatable detent engaging said closure means and holding them in their closed positions against the action of said spring means, said rotatable detent comprising a shaft carrying a notched disk opposite each of said bottom closures, the said notched disks being positioned on said shaft with their respective notches angularly displaced from one another, and means for rotating said detent comprising a freely rotatable disk having a plurality of peripheral notches of different depths therein and a lever having one end in engagement with said detent and the other end engageable with the notches of said freely rotatable disk.

7. In a vending machine, the combination comprising a plurality of token magazines having individual bottom closure means, spring means engaging said closure means and urging them to their open positions and a rotatable detent engaging said closure means and holding them in their closed positions against the action of said spring means, said rotatable detent comprising a shaft carrying a notched disk opposite each of said bottom closures, the said notched disks being positioned on said shaft with their respective notches angularly displaced from one another, and means for rotating said detent comprising a plurality of freely and independently rotatable disks supported coaxially, each of said disks having a plurality of peripheral notches of different depths therein and a lever having one end in engagement with said detent and the other end engageable with the notches of said freely rotatable disks.

ARDON A. BRADT.
